UNITED STATES PATENT OFFICE.

JAMES L. MCQUARRIE, OF MONTCLAIR, NEW JERSEY, AND HENRY P. CLAUSEN, OF MOUNT VERNON, NEW YORK, ASSIGNEES TO WESTERN ELECTRIC COMPANY, INCORPORATED, OF NEW YORK, N. Y., A CORPORATION OF NEW YORK.

TELEPHONE SYSTEM.

1,296,679.

Specification of Letters Patent. Patented Mar. 11, 1919.

Application filed August 2, 1917. Serial No. 184,028.

To all whom it may concern:

Be it known that we, JAMES L. MCQUARRIE and HENRY P. CLAUSEN, citizens of the United States, residing at Montclair, in the 5 county of Essex and State of New Jersey, and at Mount Vernon, in the county of Westchester and State of New York, have invented certain new and useful Improvements in Telephone Systems, of which the 10 following is a full, clear, concise, and exact description.

This invention relates to telephone systems, and particularly to systems wherein machine-ringing of called subscribers is employed.

It is the practice to signal a called party by intermittently ringing the bell at the substation. This is done automatically by a ringing machine at the connector, such machine having a commutator on the shaft or equivalent means for intermittently breaking the flow of ringing current. It frequently happens that the brushes of a connector are set on the terminals of a wanted 25 line during what is known as the silent interval of the ringing machine, that is, during the interval when ringing current is cut off from the line, and battery current is substituted. This results in loss of time and is 30 considered a disadvantage in commercial systems.

The object of this invention is to provide a circuit arrangement whereby ringing current is applied to the called line for a short 35 interval immediately after the connector is set thereon, and intermittently thereafter, if the called subscriber does not respond to such preliminary signal.

A feature of the present invention is a 40 ringing relay arranged to release slowly when energized over one circuit, and to release quickly when energized over another circuit. According to this feature, the relay is initially energized, immediately after 45 the called line is seized, in such a manner that it will release slowly, and thereby apply ringing current to the called line for a definite interval. When, thereafter, it is energized over a circuit including an interrupter, 50 its energization is such that it releases quickly and moves its armatures in synchronism with the interrupter.

It is thought the invention will be better understood by reference to the accompany-

ing drawing in which a connection between two substations, through the use of a connector switch embodying the present invention, is diagrammatically illustrated.

The subscriber at substation S¹, upon removing his receiver from its hook, has his line automatically extended to the selector switch SS in any well-known manner. Through the manipulation of his dial switch D, he may cause the selector switch SS to seize the connector switch CS, whereupon 65 a circuit is established from ground, lower winding of line relay LR¹, the normal contact and lower inside armature of relay LR², the lower limb of the telephone line, to and through the apparatus of the subscriber's 70 substation S¹, the upper limb of the telephone line, the upper armature and normal contact of the line relay LR², the upper winding of line relay LR¹, to battery and ground. The line relay LR¹ attracts its 75 armature and establishes a circuit from ground, the armature and alternate contact of relay LR¹, the winding of first slow relay FS, to battery and ground.

The first slow relay FS attracts its armatures and places a ground on the third conductor of the seized connector switch, whereby other selector switches are prevented from extending connections thereto. This ground, extends through the contact and 85 outer armature of relay FS to the terminal t.

At the same time, a circuit is prepared for the second slow relay SR, so that, upon the first retraction of the armature of relay LR¹ 90 in response to the circuit interruptions caused by the dial switch D, current flows over a path from ground, the armature and normal contact of relay LR¹, inner armature and alternate contact of first slow relay FS, 95 the winding of second slow relay SR, the winding of primary magnet PM, the first position contact and wiper W¹ of the side switch, to battery and ground. The second slow relay, being slow to release, remains 100 energized throughout the sending of the impulses, but the primary magnet PM not having such characteristics, responds to each separate impulse, and, through its actuation, drives the brushes b¹, b² and b³ into association with the group of terminals in which are included those connected to the substation S². The actuation of the second slow

relay SR establishes a circuit from ground, the armature and alternate contact of relay SR, the winding of escape magnet E, to battery and ground, whereby the relay E is 5 energized.

Upon the termination of this series of impulses, the second slow relay SR is 10 energized, due to the comparatively long interval during which the line relay LR¹ holds its armature in the attracted position. The consequent deenergization of the escape magnet E causes the movement of the side switch wipers into their second position.

It should be noted at this point that, upon 15 the first movement of the brushes caused by the primary magnet PM, the primary off-normal contacts PON are actuated, and the release magnet RM connected with the normal contact of the inner left-hand armature 20 of relay FS so that, if, at any time after the connector switch CS has been seized, the relay LR¹ retracts its armature for a sufficient length of time to allow the first slow relay FS to deenergize, the release 25 magnet will be energized and cause the restoration of the connector switch.

The last set of impulses sent out by the dial switch D causes the energization of the secondary magnet SM and the second 30 slow relay SR through a circuit extending now from the winding of second slow relay SR through the upper contact and armature of the test relay TR, winding of secondary magnet SM, second position contact and 35 side-switch wiper W², to battery and ground. Since the functioning of the test relay TR forms no part of the present invention, and since its operation is well known and can be easily followed from the drawing, no 40 further description will be given. Responsive to the impulses flowing through the circuit just described, the secondary magnet SM moves the brushes b² to b³ inclusive into association with the terminals t¹ to t³ inclusive, whereby the lines leading to substation S² (assumed to be idle) are seized: At the 45 termination of this series of impulses, the escape magnet E is again deenergized and the side switch wipers are moved into their 50 third positions.

In the third position, a circuit is established from ground, side-switch wiper W² and its third position contact, winding of relay 1, battery, and ground, whereby relay 55 1 is energized and attracts its armatures to extend the talking conductors, leading from the armatures of the ringing relay RR, to the brushes b¹ and b² respectively.

It should be noted that while in the second 60 position the side-switch wiper W² extended a connection from ground through the upper winding of relay RR, to battery and ground. The upper winding of relay RR is so wound that enough current flows 65 through the circuit just described to not only

energize the relay but to cause it to be slow to release when this current ceases to flow. As the side switch is moved into the third position, a circuit is then established, by the energization of relay 1, extending from 70 ground, the ringing current generator G, the alternate contact and upper armature of the relay RR, the upper armature and contact of relay 1, brush b¹, terminal t¹, to and through the call bell of the substation 75 S², terminal t², brush b², the contact and lower armature of relay 1, the inner lower armature and alternate contact of relay RR, to ground. The relay RR, being slow to release, maintains this circuit for a definite 80 interval.

As the third position of the side switch is reached a circuit is also established from ground, the side-switch wiper W² and its third position contact, outer lower armature 85 and contact of relay RR, the side-switch wiper W² and its third position contact, the winding of escape magnet E, to battery and ground. When the relay RR finally releases its armatures, the described circuit for the 90 energization of escape magnet E is opened, the escape magnet deenergizes, and the side-switch wipers move into their fourth position.

In the fourth position, a circuit is established from ground, the interrupter I, the lower winding of relay RR, contact and upper armature of the relay 2, the fourth position contact and side-switch wiper W¹, to battery, and ground. The lower winding of release relay RR is so proportioned that the current flow in this circuit, while sufficient to cause its energization, is insufficient to impart the slow releasing characteristic, this being a function of the ampere 105 turns, as is well known. Through this circuit, relay RR is intermittently energized and deenergized, and, in response, it intermittently attracts and retracts its armatures.

When, in response to the summons of his 110 call bell, the subscriber at substation S² removes his receiver from the hook and the relay RR next becomes deenergized, a circuit is established from ground, the lower winding of relay LR², the lower talking conductor of the connector switch, the normal contact and inner lower armature of relay RR, the lower armature and contact of relay 1, the brush b², terminal t², to and through the apparatus of the substation S², the terminal 120 t¹, brush b¹, contact and upper armature of relay 1, the upper armature and normal contact of the relay RR, the upper talking conductor of the connector switch, the upper winding of relay LR², to battery and ground. Relay LR² attracts its armatures and establishes a circuit from ground, the lower contact of PON, the lower armature and contact of relay LR², the winding of relay 2, the fourth position contact and side- 130

switch wiper W^1 , to battery and ground. The consequent energization of relay 2 opens the energizing circuit of the relay RR at the upper armature and contact of relay 2, and closes a holding circuit for itself through its contact and lower armature in parallel with the contact and lower armature of relay LR².

The relay 1 is maintained energized, during the conversation, through a circuit extending from ground, fourth position contact and side-switch wiper W^4 , the armature and contact of escape magnet E, the winding of relay 1, to battery and ground.

At the close of the conversation, the de-energization of relay LR¹ causes the deenergization of the first slow relay FS, which establishes a circuit from ground, armature and normal contact of relay LR¹, inner armature and normal contact of the relay FS, upper contact of PON, through the winding of the release magnet RM, to battery and ground, whereupon the connector switch is released in the well known manner. The removal of the ground potential from the terminal t through the deenergization of the first slow relay FS allows the release of the selector switch SS.

What is claimed is:

1. In a telephone system, the combination with telephone lines, a call bell associated with each of said lines, switching means for interconnecting said lines and a source of ringing current for actuating said call bells, of a slow-releasing relay having two windings included in said switching means for controlling the application of said ringing current to said lines, a transient circuit including one of said windings for the energization of said relay established upon the seizure of one of said lines as a called line by said means, and a circuit including an interrupter and the other of said windings for the subsequent energization of said relay.
2. In a telephone system, the combination with telephone lines, a call bell associated with each of said lines, a connector switch in which said lines terminate, means for setting said connector switch on said lines and a source of ringing current for actuating said call bells, of a relay having a high resistance and a low resistance winding for controlling the application of said ringing current to said lines, a transient circuit including the low resistance winding of said relay, for the initial energization of said relay, and a circuit including an interrupter and said high resistance winding of said relay for the subsequent energization of said relay.

ing said call bells, of a relay having two windings for controlling the application of said ringing current to said lines, a transient circuit including one of said windings for the initial energization of said relay, and a circuit including an interrupter and the other of said windings for the subsequent energization of said relay. 55

3. In a telephone system, the combination with telephone lines, a source of ringing current and switching means for interconnecting said lines, of a slow-releasing relay for controlling the application of said current to said lines, a transiently-established circuit for the initial energization of said relay, a 65 circuit including an interrupter for the subsequent energization of said relay, and means included in said last circuit for reducing the flow of current therover for causing said relay to be quick to release. 70

4. In a telephone system, the combination with telephone lines, a source of ringing current, switching means for interconnecting said lines, of a relay for controlling the application of said current to said lines, a transiently-established circuit including means for the strong energization of said relay, and a circuit including an interrupter and means for the weak energization of said relay. 75

5. In a telephone system, the combination with telephone lines, a call bell associated with each of said lines, a connector switch in which said lines terminate, means for setting said connector switch on said lines and a source of ringing current for actuating said call bells, of a relay having a high resistance and a low resistance winding for controlling the application of said ringing current to said lines, a transient circuit including the low resistance winding of said relay, for the initial energization of said relay, and a circuit including an interrupter and said high resistance winding of said relay for the subsequent energization of said relay. 95

In witness whereof, we hereunto subscribe our names this 1st day of August A.D., 1917.

JAMES L. McQUARRIE.
HENRY P. CLAUSEN.
